UNITED STATES PATENT OFFICE.

CHARLES STILWELL, OF MORRISTOWN, NEW JERSEY.

THILL-COUPING.

SPECIFICATION forming part of Letters Patent No. 375,220, dated December 20, 1887.

Application filed March 12, 1887. Serial No. 230,706. (No model.)

To all whom it may concern:

Be it known that I, CHARLES STILWELL, of Morristown, New Jersey, have invented a new and useful Improvement in Thill-Couplings, 5 of which the following is a specification.

My invention consists of improved contrivances for a detachable connection of the thills of a buggy to the axle-clips without the employment of any adjustable part—as a spring-nut, key, or screw—and so that the joints will not become noisy with the slack of wear, and also so that the connection and disconnection can be made in the most simple and ready manner, all as hereinafter fully described, reference being made to the accompanying drawings, in which—

Figure 1 is a plan view of my improved thill-coupling. Fig. 2 is a side elevation of the axle-clip and longitudinal section of the 2c thill-iron, the thill being in the position of use. Fig. 3 is a side elevation of the coupling entire in the same position. Fig. 4 is a side elevation of the axle-clip and section of the thill-iron, showing the position of the thills 25 for effecting the connection or disconnection.

The axle-clip *a* is made with a pivot-bearing hook, *b*, to receive the pivot *c*, which is carried in the forks *d* of the thill-iron *e*, said hook having an opening in the top to receive the 30 pivot, which is rigidly secured in the forks. The center of said opening is a little back of the vertical plane of the pivot-bearing of the hook, and its breadth from *f* to *g* is from a quarter to a third, or thereabout, less than the 35 diameter of the pivot and the bearing therefor to which said opening is the entrance. The pivot is correspondingly flattened at *h*, which is its upper side when the thills are in the working position, and is then coincident 40 with the opening. The rest of the pivot, being of full size, fills the wider portion of the bearing below the opening, and is therefore confined and secured in its position by the convergent points *f* *g* above. The pivot is inserted or removed through the opening by 45 turning the thills up perpendicularly, as represented in Fig. 4, which shifts the pivot so that its narrower section will pass through the opening.

For a safeguard against the possible escape of the pivot by any sharp thrust or wrench

that may happen, and also to prevent noise by rattle in case of slackness, I arrange the roller *i* in ears *j* of the pivot, forked under the pivot and so as to swing and roll along a portion, *k*, of the hook concentric with the bearing, and thus keep the pivot down on its bearing. This roller may be made of metal or any hard and slightly-elastic substance—as rubber, vulcanized fiber, or the like. This roller-guard is more positive and avoids the friction and wear of the sliding guard with a spring behind it, which has been tried. To facilitate the inserting of the pivot and removal of it through the opening, provision is made for a 65 little slackness of the upper end of the hook between the pivot and roller by making the hook narrower from its end down to the concentric part *k*, so that the pivot may not be obstructed in its passage through the opening, 70 and less care will be required as to the position of the uplifted thills for inserting the pivot.

In a space at the front of the bearing-hook and between the forks *d* of the thill-iron I arrange a block-spring, *l*, of elastic rubber, as a further means of preventing the rattling of slackness, said spring being placed in its position without any special fastening, but being secured by the forks the projecting end 80 *m* of the thill and the bottom piece, *n*, the latter being a thin plate that may be welded or otherwise secured on the thill-iron, if welded on the spring, may be put in position before the pivot *c* is put in, and said pivot may be detachably secured in the forks for renewal of the springs and of the pivot. The spring may, however, be crowded into its place without removal of the pivot when the thills are turned upright, provided the projection *m* of the thill 90 be a little shorter.

The hook is thinner at the point than where the spring bears on it, in order that it shall not catch the spring when the thills are turned down after having been raised upright for any 95 purpose, and so that the spring will come to an effective bearing when the thills are down to the working position.

To relieve the pivot *c* and roller *i*, and also to relieve spring *l*, to some extent of their 100 tension when the carriage is not in use; I construct the hook *b* with a recess, making some-

what less radius at *o*, where the roller comes to rest when the thills are let down on the floor, and to prevent the collection of mud and dust in the pivot-bearing I arrange a 5 rubber, leather, or other dust-guard, *p*, over it, said guard consisting of a flat strip connected by one end to the clip *a* for attachment, and reacting forward at the other end, which is unattached, over the spring *l* to the end of projection *m* of the thill and beyond the hook, so that when the thills are to be connected the free end of said guard may be raised by presenting the pivot under it and raising the pivot over the hook by carrying the thills nearly in 10 an upright position in the hands.

It will thus be seen that with this improved coupling the connection may be made by simply taking the thills in the hands, presenting them in the upright position, lifting the 15 guard by the pivots, dropping the pivots into the bearings and turning the thills down, and the disconnection requires only the raising of the thills to the upright position and lifting the pivots out, no extra piece of any kind being used, and all the trouble and the waste by 20 loss of such devices are avoided, besides the accidents that happen in consequence of the loss of fastenings.

I make the clip with thrust-bearings *g*, and 25 the pivot-forks with thrust-extensions *s*, to relieve the pivots of the back-thrusts of sudden stops and of backing the carriage, said bearings and extensions being curved correspond-

ingly to the radius of the pivot, so as to bear properly in the changing action of the projections by the motions of the horse. 35

What I claim, and desire to secure by Letters Patent, is—

1. The combination, with the clip-hook having the open bearing for the pivot of the thill-iron rigidly connected in the forks of said iron, 40 of a guard under the concentric portion of the hook, consisting of a roller pivoted in the ears of the pivot-forks, substantially as described.

2. The combination of the spring *l* in the 45 recess of the pivot-forks with said pivot, the pivot-bearing hook, and the guard-roller, substantially as described.

3. The pivot-bearing hook having the recess *o* back of the concentric portion *k*, in combination with guard-roller *i*, spring *l*, pivot *e*, and the pivot-forks, substantially as described. 50

4. A thill-coupling consisting of the pivot-bearing hook formed on the clip and the pivot-carrying fork formed on the thill-iron, said 55 clip having a thrust-bearing on each side of the hook curved radially to the pivot-bearing, and the pivot having an extension of each prong similarly curved and respectively co-acting with said thrust-bearings for resisting the back-thrusts, substantially as described. 60

CHARLES STILWELL.
